UNITED STATES PATENT OFFICE.

WALTER EDWARDS WARNER, OF BROOKLYN, NEW YORK.

DENTAL-SERVICE STAND.

SPECIFICATION forming part of Letters Patent No. 448,100, dated March 10, 1891.

Application filed March 8, 1890. Serial No. 343,122. (No model.)

To all whom it may concern:

Be it known that I, WALTER EDWARDS WARNER, of Brooklyn, in the county of Kings and State of New York, have invented a new 5 and Improved Dental-Service Stand, of which the following is a full, clear, and exact description.

My invention is an improvement in the class of dental stands which are provided 10 with a spittoon attached to a service or waste pipe; and the improvement consists in the construction and combination of parts, as hereinafter described.

Reference is to be had to the accompanying 15 drawings, forming a part of this specification, in which similar figures of reference indicate corresponding parts in all the views.

Figure 1 is mainly a central vertical section through the device, a portion of the same 20 being in side elevation. Fig. 2 is a partial side elevation and section of the branch or movable waste-pipe and a vertical section through the adjusting-plug used in connection therewith. Fig. 3 is a horizontal section 25 taken on line *x* *x* of Fig. 2, the plug being illustrated in a position to be slipped upon the service-pipe.

In carrying out the invention the waste-pipe 10 is carried upward some distance above 30 the floor and is provided at its upper end with an attached outwardly and upwardly flaring socket 11, having a ground inner surface. Into the upper end of the waste-pipe the end of the vertical member of a curved 35 or essentially L-shaped branch pipe 12 is introduced, the said end of the branch being reduced in external diameter at its extremity and provided with a gasket or packing 13, of any approved material, engaging with the inner surface of the main waste-pipe 10, thereby 40 forming a water and gas tight connection. The vertical member of the branch waste-pipe 12 has produced upon opposite faces a series of vertically-aligning lugs 14, as best 45 shown in Fig. 2.

Upon the branch pipe 12 a disk-like plug 16 is slid, shaped with ground beveled sides and adapted to fit in the socket 11 and form a ground swing-joint between the main waste-pipe 50 and its branch. The plug 16 is fitted with a bore of sufficient diameter to take the vertical member of the branch pipe 12,

and also with interior perpendicular grooves 15 to clear the lugs 14 of the branch pipe, and with circumferential grooves forming ribs 17, 55 adapted to pass between the lugs of the branch pipe, as shown in Fig. 3. The plug is placed upon the branch 12 by causing the lugs 14 of the branch to enter the perpendicular grooves or channels 15 of the plug, and 60 the horizontal member of the branch waste-pipe may be held at more or less elevation above the main waste-pipe by turning the plug and causing the ribs 17 to pass under and in contact with the upper or the lower 65 branch lugs 14, as illustrated in Fig. 2.

Upon the extreme end of the horizontal member of the waste branch pipe 12 a globe-trap 18 is secured, having a plug screwed in 70 its under side and provided with an opening in its top of sufficient diameter only to receive the tubular shank 19 of a cup or spittoon 20, communication being established between the bottom of the globe-trap and the spittoon through said shank. 75

It is obvious from the foregoing description that by the manipulation of the plug 16 the spittoon may be raised or lowered, as it is carried by the waste branch pipe 12, and that as said branch may be turned freely in the 80 main waste-pipe the spittoon may be readily moved horizontally in a circle.

Through the lower portion of the main waste-pipe 10 the service-pipe 21 is entered, which service-pipe is carried upward through 85 the main waste-pipe and the vertical member of the branch 12 and out through a suitable stuffing-box 22, formed upon the latter. The upper portion of the service-pipe has attached thereto a faucet 23, preferably of the goose-neck pattern, and below said faucet a glass-holder 24 is affixed to the service-pipe or the faucet. 90

Within the basin or spittoon 20 a spray 29 is located, which is connected by a flexible 95 tube 30 with the stop-cock 31, attached to the service-pipe by a swing-joint.

An urn 32 is secured to the ring of the glass-holder, provided with a suitable cock and having secured to its lower end a flexible 100 tube 34 of sufficient length to extend downward in the basin or spittoon, the said tube 34 being provided with a branch tube 35. By permitting the water to run through the tube

34 into the basin or spittoon a gentle suction is created in the branch tube 35, whereby the latter may be employed with good results to siphon saliva from the patient's mouth. The 5 drinking-glass is supported in the ring-like body of the holder.

Having thus described my invention, I claim as new and desire to secure by Letters Patent—

10 In a stand for dental use, the combination,

with the vertical waste-pipe 10 and the detachable bored plug 16, supported therein and having internal grooves and ribs, of the laterally-extended pipe 12, carrying a spittoon, and the spray 29, located within it, all as 15 shown and described.

WALTER EDWARDS WARNER.
